UNITED STATES PATENT OFFICE.

WILLIAM H. SAUVAGE, OF BUFFALO, NEW YORK, ASSIGNOR TO SAUVAGE APPLIANCE COMPANY, OF NEW YORK, N. Y.

RAILWAY BRAKE.

Application filed May 13, 1920. Serial No. 381,061.

To all whom it may concern:

Be it known that I, WILLIAM H. SAUVAGE, a citizen of the United States, residing at Buffalo, in the county of Erie and State of New York, have invented certain new and useful Improvements in Railway Brakes, of which the following is a specification.

This invention relates to improvements in railway brakes and more particularly to the foundation brake rigging of railway cars of all kinds.

One of the objects of the present invention is to provide an improved railway brake mechanism particularly adapted for use on the under side of railway cars of either the passenger or freight car type, which will be of simple and practical construction, quick acting and exceedingly high powered.

20 A further object is to provide a brake mechanism of the above general character which will be far more efficient than the brake system now in use and which may be applied to the present equipment without extensive alteration or addition.

25 A further object is to provide a brake system of the last above character having relatively few parts which may be inexpensively manufactured and assembled.

30 A further object is to provide an improvement to the present system which may be cut in and out at will as circumstances demand.

Other objects will be in part obvious and 35 in part hereinafter pointed out.

Reference is made to the accompanying sheets of drawings forming part of this disclosure and wherein one of various possible embodiments of the system is illustrated and in the several views of which corresponding elements are denoted by similar reference characters.

In these views,

40 Figure 1 is a plan and semi-diagrammatic view of such parts of the complete system as are necessary to understand the same, certain parts being shown in section or broken away for the sake of clearness.

45 Figure 2 is a sectional view of the two-way check valve.

Figure 3 is a sectional view of a modified form of check valve.

Figure 4 is a plan view partly in section showing the automatic take-up connection.

Figure 5 is a view at right angles to Figure 4 of the part shown therein.

Figure 6 is a detail view of certain parts shown in Figures 4 and 5.

Referring now to the drawings in detail and more particularly to Figure 1, 10 denotes the main power cylinder at one end of which is positioned a fulcrum or jaw 11 supporting one end of a dead lever 12. The opposite end of said lever has pivotally connected thereto at 13 a pull rod 14 leading to the truck brake rigging at one end of the car.

The cylinder 10 is provided with a piston 15 pivotally connected to one end of live lever 16, the opposite end of which is pivoted at 17 to one end of a pull rod 18 leading to the truck brake rigging at the opposite end of the car. The cylinder levers 12 and 16 are connected by a tie rod 20.

The relative positioning, proportioning and location of these parts are all well-known to those skilled in the art and need no further description. It is sufficient to state that the proportions and positioning may be arranged according to circumstances as desired and where the mechanism is applied to a single truck car such as is occasionally found in street railways, further modifications are necessary.

Air is admitted to the cylinder 10 through a pipe 21 connected with triple valve 22 which in turn is connected with an auxiliary reservoir by pipe 23 and the usual train brake pipe 24, these parts being shown merely diagrammatically and are located wherever convenient on the car.

It will be noted that the piston 15 is provided with an extension or a pull rod 25 having an eye 26 at its end which is connected by means of chain 27 to hand brake mechanism in the usual manner diagrammatically indicated at 28 thus permitting the car to be braked by the hand brake when disconnected from a source of air.

Adjacent the cylinder 10 is a second power

cylinder 30 of any desired shape and size being provided with a source of air through pipe 31 leading to the rear of the piston within the cylinder 10. A main cut-out valve 5 32 is provided for disconnecting this attachment and a two-way check valve 33 indicated more clearly in Figures 2 and 3 permits flow of air as hereinafter described.

Referring briefly to Figure 2 it will be 10 noted that this check valve casing 33 is provided with two chambers 34 and 35 connecting the two parts of the pipe 31. The dividing partition 36 is provided with valve seats and valves 37 and 38 respectively on its opposite sides both being held in place by springs 40, the predetermined tension of which may be adjusted by means of nuts 41. In this manner air pressure necessary to 15 overcome the check valves both in actuating 20 the piston and permitting release through the triple valve after actuation can be controlled.

The cylinder 30, Figure 1, is, of course, 25 provided with a piston 42 which is pivotally connected at 43 to one end of a lever 44, the opposite end of which lever is pivoted at 45 to a fixed bracket or other support 46 secured to the under side of the car body. The lever 44, as shown in Figure 6, is provided 30 with a central opening 47 in which is mounted a member 48 trunnioned to the lever at 50 so as to be movable therewith. This member 48 carries a dog 51, Figure 4, having an opening through which the rod 25 is adapted 35 to pass. In the normal position, as shown in Figure 4, a spring 52 is compressed between one side of the dog 51 and member 48. The dog is held in a position normal to the rod 25 by means of a stop 53 on one side and 40 a push pin 54 on the other, the pin 54 engaging an abutment 55 carried by the supporting bracket 56.

In Figure 3 there is shown a modified form of check valve adapted to be interposed between the same cylinders as in the 45 relation shown at 33 in Figure 1. The principal difference between this check valve and that shown in Figure 2 is that when a predetermined pressure is obtained under valve 50 stem 60 it rises and the air then immediately gets under the packing leather piston or diaphragm piston 61 which by reason of its larger area holds the port 62 open so that the return check valve 63 could be dispensed 55 with if necessary. On release of the brakes the large piston or diaphragm 61 holds the valve port 62 open until practically all the air has been exhausted to the atmosphere through the triple valve. Now referring to 60 the double inlet valve shown in Figure 2, the check valve has a tendency to remain closed even after admitting air past its seat and will not allow proper equalization of pressure greater than the spring differential

which, let it be assumed, is ten pounds. With 65 the valve shown in Figure 3 the brake cylinders are allowed to equalize at the same pressure, that is, fifty pounds in both cylinders instead of possibly fifty pounds in one cylinder and forty pounds in the supplementary or auxiliary cylinder. 70

With this structure in mind it is believed 75 that the operation of the system will be clear from the following statement:—

When air is admitted in the usual way by 80 the engineer through the action of the triple valve 22 connected to the standard auxiliary reservoir this air forces out the piston 15 taking up all of the slack and applying the 85 brakes to the wheels through the live and dead levers, brake beams and shoes and associated mechanism as above described. If not more than ten pounds of air or other 90 predetermined amount is admitted to the cylinder 10 no air will pass through the pipe 31 and controlling valves 38 and the tie rod 25 passes freely through the dog 51 and 95 associated parts, the dog being held at right angles to this rod 25 by means of the pin 54 which holds it thus by being forced against 100 the lever guide at 55. Should more than ten pounds of air be admitted to the cylinder 10 the inlet check valve 38 to the cylinder 30 will open allowing air to pass into the cylinder 30 and actuate the piston 42 which 105 on moving very slightly will release the pin 54 and allow the dog 51 to go into action on the tie rod 25 so that both cylinders will be working together to the full pressure that may be admitted. Owing to the action of 110 this mechanism very little piston travel is derived from cylinder 10 but great power is produced by action of the pressure in cylinder 30 because of the double leverage as shown.

When the brakes are released through the 115 action of the triple valve 22, air passes out through the outlet check valve 37 in the valve casing 33 and discharges into the atmosphere through the triple valve in the usual manner. When the piston on the cylinder 30 nearly reaches its full release position the pin 54 strikes the lever guide 55 or other fixed stop provided for this purpose, thereby unlocking the dog 51 from its action 120 on the tie rod 25 and allowing it to freely go into full release position.

When emergency application is made cylinder 10 drives out all the slack in the brake rigging before the cylinder 30 goes into action thereby allowing the air pressure in both cylinders to equalize high. Thus without equipping the car with expensive mechanism and larger and extra auxiliary reservoirs, expensive complicated control valves, etc., braking powers can be increased nearly 125 200% without requiring special triple valve and increased pump and air capacity.

For freight cars, no triple valve to date has been perfected for larger than ten inch brake cylinders so the construction herein shown is preferable for heavy cars requiring braking power to permit handling cars of over fifty tons capacity.

The hand brake chain is attached in the manner herein shown and described thus permitting an operation of the rod 25 and 10 associated parts in the usual manner. The leverage and the diameter of cylinders can be proportioned to suit the load or braking conditions and the cut-out cock 32 will permit the second cylinder attachment to be 15 dispensed with at will. Extensive tests have proven however that the use of the hand-brake is not to be recommended. With ten-inch cylinders a 120 ton car can be braked 40% empty and 40% loaded by normally 20 opening and closing the cut-out cock 32. The piston rod in cylinder 30 is directly attached to the lever 44 and trunnion box 48 to always release the dog 51 when this lever moves into full release position thus forcing 25 the unlocking pin 54 to trip the dog and hold it stationary when the hand brakes are applied. No matter what the piston travel of cylinder 10 may be cylinder 30 does not go into action until the pressure under the 30 inlet check valve in control valve 33 overcomes the spring pressure on said inlet check valve 38.

It is thus seen that the present invention provides a simple and practical construction 35 adapted to accomplish, among others, all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, 40 and therefore such adaptations should and are intended to be comprehended within the meaning and range of equivalency of the following claims.

What I claim is: —

50 1. In a brake system, in combination, a power cylinder having live and dead levers associated therewith, an auxiliary cylinder connected with the power cylinder, means connecting the auxiliary cylinder with the live lever, and an automatic control valve in the connecting means between said cylinders whereby said auxiliary cylinder goes into operation when the pressure admitted 55 to the main cylinder exceeds a predetermined pressure, and means whereby pressure within the two cylinders is equalized at high pressure.

60 2. In a brake system, in combination, a main cylinder connected with a source of

air pressure, live and dead levers connected therewith, an auxiliary cylinder connected with the main cylinder, automatic double acting control check valves in said connecting means adapted to distribute and equalize the pressure within said cylinders, and a lever associated with said auxiliary cylinder and connected with said live lever whereby said live lever is actuated by both cylinders when said control check valve is overcome on excess pressure.

75 3. In a brake system, in combination, a main power cylinder, a piston associated therewith, live and dead levers operatively connected with the piston and adapted to be actuated thereby, a two-way automatic control valve adapted to be actuated at a predetermined pressure and to equalize high pressure between said main cylinder and an auxiliary cylinder having a piston operatively connected with said first mentioned piston, means whereby said first mentioned piston may be actuated separately or with said auxiliary piston, and means whereby said valve may be manually set for actuation at any desired pressure.

80 4. In a brake system, in combination, a main power cylinder connected with a source of air pressure and having a piston, an extension associated with said piston, live and dead levers operatively connected with said piston, an auxiliary cylinder having a piston, and a normally inactive connection between said auxiliary piston and the extension to said main piston adapted to permit independent operation of the main piston 95 and simultaneous operation of both pistons, means adapted to operate both cylinders at the highest mean pressure when the pressure on said main piston exceeds a predetermined pressure.

100 5. In a brake system, in combination, a main power cylinder connected with a source of air pressure and having a piston, an extension associated with said piston, live and dead levers operatively connected with said piston, an auxiliary cylinder having a piston, a means interposed whereby the maximum pressure in said auxiliary cylinder is equalized between the said main and auxiliary cylinders, a normally inactive connection between said auxiliary piston and the extension to said main piston adapted to permit operation of the main piston or simultaneous operation of both pistons, said connecting means comprising a self-locking device having a position normal to said extension and means for throwing said dog lock device into canted or locked position with respect to said piston when said auxiliary piston is actuated.

115 6. In a brake system, in combination, a main cylinder connected with a source of air, a main piston having an extension, live

and dead levers associated with said piston adapted to be actuated thereby, an auxiliary cylinder having a pipe connecting it with the main cylinder, a double automatic check valve in said pipe adapted to be actuated on predetermined pressure and to equalize the pressure in said cylinders, a lever passively connecting said auxiliary piston with said extension and means adapted to actively connect said lever with said extension when said auxiliary piston is actuated.

7. In a brake system, in combination, a main power cylinder having a piston provided with an extension, actuated mechanism connected with said piston, an auxiliary cylinder and piston, means for supplying air thereto, a lever connected with said second piston and normally disengaged from said extension, and means for automatically 20 engaging said lever with said extension when said auxiliary piston is actuated and means for equalizing pressure between said cylinders.

8. In a brake system, in combination, a main power cylinder having a piston provided with an extension, actuated mechanism connected with said piston, an auxiliary piston, means for supplying air thereto and means for equalizing the pressure 30 therein with the pressure in said main cylinder, a lever connected with said second piston and normally disconnected with said extension, and means for automatically connecting said lever with said extension when 35 said auxiliary piston is actuated, said means comprising a dog carried by said lever through which said extension passes, and means normally holding said dog unlocked or at right angles to said extension.

40 9. In a brake system, in combination, a main power cylinder having a piston provided with an extension, actuated mechanism connected with said piston, an auxiliary piston, means for supplying air thereto and for automatically raising the pressure 45 in the main cylinder to a mean with the pressure in the auxiliary cylinder, a lever connected with said second piston and normally disconnected with said extension, means for automatically connecting said 50 lever with said extension when said auxiliary piston is actuated, said means comprising a dog carried by said lever through which said extension passes, means normally holding said dog at right angles to said extension, and means for automatically canting 55 said dog and holding it in gripping relation to said extension when said auxiliary piston is actuated.

60 10. In a brake system, in combination, a power cylinder, and piston means adapted to be reciprocated by the piston thereof, an auxiliary power cylinder and mechanism normally disconnected from said means, and

means for connecting said auxiliary power mechanism with said first means on excess pressure in said main power cylinder and for equalizing said excess pressure in said power cylinders.

11. In a brake system, in combination, a main power cylinder having a piston, an extension connected with said piston and reciprocating therewith, a double acting control valve whereby pressure passes to an auxiliary cylinder and is equalized between the said cylinders, normally disconnected means between said cylinder and said extension comprising a dog and means normally holding said dog in a position at right angles to said extension, said last means comprising a spring urging the dog into biting engagement and a pin and fixed stop urging the dog in the opposite direction when the parts are returned to normal position.

12. In a brake system, in combination, a power cylinder having a piston, an extension adapted to reciprocate with said piston, an auxiliary cylinder without leakage groove and piston, a pressure equalizing valve, a lever connected with said auxiliary piston, a fixed part, and means carried by said lever and normally disconnected with said extension adapted to automatically connect with said extension when said auxiliary piston is actuated.

13. In a brake system, in combination, a power cylinder having a piston, an extension adapted to reciprocate with said piston, a non leakage groove auxiliary cylinder and piston, a control valve adapted to distribute 100 and equalize pressure, a lever connected with said auxiliary piston, a fixed part, means carried by said lever and normally disconnected with said extension adapted to automatically connect with said extension when said auxiliary piston is actuated, and means adapted to restore said connecting means to disconnected position when the parts are returned to full release position.

14. In a brake system, in combination, a main power cylinder, an auxiliary cylinder, a pipe connecting said cylinders, double check valves in said pipe permitting air to flow in either direction and an equalized air pressure on application and release of 115 the brakes.

15. In a brake system, in combination, a main power cylinder, an auxiliary cylinder, a pipe connecting said cylinders, check valves in said pipe permitting air to flow 120 and equalize pressure in either direction on application and release of the brakes, and means for connecting the auxiliary piston with the main piston when air flows from the main cylinder to the auxiliary cylinder.

16. In a brake system, in combination, a main power cylinder, an auxiliary cylinder, a pipe connecting said cylinders, a check

valve in said pipe automatically controlling the flow of air and equalizing the pressure permitting air to flow in both directions on application of the brakes, means for connecting the auxiliary piston with the main piston when air flows from the main cylinder to the auxiliary cylinder, and hand

brake mechanism associated with said power brake mechanism whereby the hand brake mechanism may be actuated independently ¹⁰ of the others.

In testimony whereof I affix my signature.

WILLIAM H. SAUVAGE.
